INVENTOR-

Warren E. Coombes

UNITED STATES PATENT OFFICE.

WARREN E. COOMBES, OF BOSTON, MASSACHUSETTS, ASSIGNOR TO UNITED SHOE MACHINERY CORPORATION, OF PATERSON, NEW JERSEY, A CORPORATION OF NEW JERSEY.

SHOE RACK.

Application filed July 19, 1926. Serial No. 123,386.

This invention relates to shoe racks such as are used to hold shoes between shoe-making operations and to carry them from one part of a factory to another during the various stages of their manufacture.

One of the most serious problems which have confronted shoe manufacturers has been that of economizing in the amount of floor space occupied by racks utilized for carrying shoes. This problem has been aggravated by the fact that care must be exercised to insure that the shoes are held in such a way as to avoid injury to them as they are carried in the racks and by the fact that during some stages in the manufacture of shoes, it is desirable or necessary to carry shoes bottom side up, and during other stages it is desirable to carry the shoes in right side up position.

In view of these facts, it has been the practice, in some factories, to make use of specially designed shoe racks of several different types in connection with the various shoe-making operations. For example, in the making room a shelf rack is employed in connection with all operations up to the operation in which the bottom filling is inserted in the shoes; in connection with that operation and subsequent operations up to the time the lasts are pulled, a rack comprising pins for supporting shoes bottom side up is utilized; and, after the lasts are pulled another type of shelf rack is employed for carrying the shoes in the treeing and packing rooms where the finishing operations are performed.

This has resulted in the necessity of maintaining at hand a large number of racks of each type employed in order that, if operations are held up at one point, workmen performing operations earlier in the process of shoe-making may be supplied with racks of the proper type. Thus, in addition to the high cost of maintaining such racks, a large amount of valuable floor space is occupied by them, and considerable storage space must be provided for surplus racks temporarily out of use.

Accordingly, with a view to reducing the cost of making shoes, some factories have made use of one type of shoe rack throughout the entire process of shoe-making. This presents the advantage that, as the racks are emptied, they can be shifted from one part

of the factory to another for use in connection with any operation for which they may be needed. In this way, the number of racks required is considerably reduced, less floor space is required than where racks of several types are used, and little or no storage space for surplus racks is necessitated.

To this end, use has been made of a rack construction of the type disclosed in United States Letters Patent No. 1,556,425, granted October 6, 1925, upon an application filed in the name of W. E. Coombes et al., which comprises relatively flat shoe-supporting members, or pins, arranged for contacting with the heel parts of uppers of shoes carried in the rack bottom side up, a toe rest being provided to assist in positioning and supporting the foreparts of the shoes.

The rack construction referred to is particularly adapted for use in carrying shoes bottom side up, in a small amount of space, without subjecting the shoes to the likelihood of injury, but at the same time is constructed and arranged for so holding the shoes that they can be readily removed from the rack. This rack is used normally for carrying lasts or shoes bottom side up between operations performed upon shoes from the time the lasts are picked until the lasts are removed from the shoes.

To adapt the rack to use in carrying shoes right side up in the treeing and packing rooms, a cover, preferably made of flannel, is placed upon the pins. This cover prevents the shoes from dropping down into the spaces between the pins, and serves to prevent discoloration of the shoes from contact with the shoe-supporting members. Thus a rack of the type referred to can be used for carrying shoes at any stage in the process of shoe-making.

One difficulty which has been experienced in using such racks in the manner above indicated is that if shoes are placed upright upon the covered pins with the heel ends of the shoes extending toward the front of the rack, the shoes ride up on the toe rest, are not evenly supported, and consequently tend to jostle one another, slide toward the back of the rack, and strike the back rail in such a way as to cause injury to the uppers of the shoes.

On the other hand, if the shoes are placed with their heel ends extending toward the

back of the rack, the counters of the shoes are likely to be scraped or gouged by contact with the back rail, especially when the covers become worn, or are discolored by the back rail or flannel cover in cases where the same rack is used successively for carrying black shoes and shoes of lighter colors. An additional objection to carrying shoes in this manner is that in order to prevent discoloration of the foreparts by contact with the hands of the operator, the shoes are grasped at the heel ends in removing them from the rack. This necessitates removal of the shoes from the back of the rack, which is inconvenient or even difficult for the reason that the shoes must be lifted over the back rail.

In view of the foregoing, the present invention provides an improved rack for carrying shoes, in which shoe-supporting and shoe-positioning members are arranged for adjustment relatively to each other to render the rack convertible for different uses.

Preferably, and as herein shown, the rack is provided with a plurality of shoe-supporting pins, across which extends a movable bar which can be located in either one of a plurality of positions along the pins by means of grooves in the body portion of the rack adapted to receive the ends of the bar. In one position the bar serves as a toe rest for shoes carried in the rack bottom side up, and in the other position the bar serves as a heel stop for shoes carried in the rack in upright position.

These and other features of the invention will be understood from the following description of a preferred embodiment of the invention and are disclosed in the accompanying drawings, in which

Fig. 1 is a perspective view of a rack embodying the present invention;

Fig. 2 is a detailed perspective view illustrating a portion of a rack with the adjustable bar in position to carry shoes bottom side up;

Fig. 3 is a detailed perspective view illustrating the bar in position to carry shoes right side up; and

Fig. 4 is a detailed view of an end of the bar.

The illustrated rack, as shown in Fig. 1, comprises bottom frame members 10 and end frame members 12 composed of steel angle sections secured together to form a rigid structure by means of braces 14 and 16, diagonals 18 and 20, and a tie rod 22. The bottom frame members 10 are provided with casters 24 and bumpers 26 of well-known construction. Spaced from the bottom members 10 are bars 28 and cross pieces 30 which form a shelf for carrying boxes containing shoe parts.

Riveted to inner portions of the end

members 12 are channel sections 32 positioned to engage and support wooden shelves 34 which constitute the shoe-supporting portions of the rack.

Each of the shelves 34 (see Figs. 1 and 2) comprises end pieces 36 connected by a back rail 38 and a pin bar 40. Secured to the upper surface of the pin bar 40 by means of screws 42 are a plurality of shoe-supporting members or pins 44, the rear ends of which are received in a groove 46 formed in the back rail 38. The pins adjacent the end pieces 36 are positioned in grooves 48. The bar 40, groove 46, and grooves 48 are inclined to the horizontal in such manner that the pins 44 are supported with their free ends tilted upwardly toward the front of the rack. The construction just described provides means for securely supporting the pins, but at the same time readily permits removal of the pins for purposes of replacement.

The pins are of the alternate wide and narrow construction disclosed in the aforementioned patent, and are adapted normally to receive and support between them shoes in inverted position with the heel end portions of the uppers of the shoes in contact with the edges of the pins.

Means is provided for assisting in the supporting and positioning of shoes either in inverted position or in upright position. As herein shown, this means comprises a bar 50 provided at each end with a tenon 52 as illustrated in Fig. 4. The end pieces 36 of each shelf are provided with two sets of substantially vertical grooves 54 and 56, equally spaced from the back rail 38 at opposite ends of the shelf and shaped to receive the tenoned ends of the bar 50 to hold it, selectively, in either one of two positions in each of which the bar extends across the pins parallel to the back rail. The two operative positions of the bar are illustrated in Fig. 1 in connection with the showing of the upper and the lower shelves respectively.

The use of the rack is best illustrated with reference to Figs. 2 and 3.

As indicated in Fig. 2, the bar 50 is positioned in the grooves 54 which operate to locate the bar in position to act as a toe rest for shoes, such as a shoe 58, the heel portion of which is supported upon the edges of the pins 44. This constitutes the normal use of the rack, and the bar 50 ordinarily will be left in the position shown until the rack is to be used as a treeing and packing room rack. The bar 50 is then removed from the grooves 54, a cover 60 of flannel, paper or other sheet material is placed over the pins, as shown in Fig. 3, and the bar is inserted in the grooves 56. In this position the bar acts as a heel stop for shoes, such as a shoe 62 placed on the cover 60, in upright position with its shank extending over the bar 50 and its heel in contact with that portion

of the bar facing toward the front of the rack. The inclination of the pins assists in maintaining the heels of shoes in contact with the bar. In this manner shoes are carried with their bottom portions firmly supported, with their uppers out of contact with the back rail of the rack, and at the same time, the shoes are so positioned with their heel ends extending outwardly as to be readily accessible from the front of the rack.

Having described my invention, what I claim as new and desire to secure by Letters Patent of the United States is:—

15 1. A shoe rack comprising a plurality of shoe-supporting members, a shoe-positioning member, and means for locating the positioning member relatively to the shoe-supporting members in positions for contacting with different portions of shoes carried in the rack at different stages of their manufacture for maintaining the shoes in position upon the supporting members.

20 2. A shoe rack comprising a plurality of shoe-supporting pins, and a bar selectively adjustable into a plurality of positions along the pins for contacting with different portions of shoes carried in the rack at different stages in the process of their manufacture 25 for maintaining the shoes either in upright or in inverted position upon the pins.

25 3. In a shoe rack for carrying shoes either right side up or bottom side up, a plurality of shoe-supporting members, a movable bar extending across the shoe-supporting members, and means selectively effective to hold the bar in position to act as a heel stop for shoes carried right side up upon the shoe-supporting members, or to hold the bar in 30 position to act as a toe rest for shoes carried bottom side up upon the shoe-supporting members.

40 4. A shoe rack comprising a plurality of shoe-supporting members, and a member adjustable along the shoe-supporting members into position to act as a toe rest for shoes carried in the rack bottom side up, or into position to act as a heel stop for shoes carried in the rack in upright position.

45 5. A shoe rack comprising a plurality of shoe-supporting pins, a movable bar extending across the pins, means for locating the bar along the pins in position to act as a toe rest for shoes carried on the pins bottom side

up, and means for locating the bar along the pins in position to act as a heel stop for shoes carried in the rack in upright position.

55 6. A shoe rack comprising members for supporting shoes in inverted position, a member for positioning shoes carried upon the supporting members, the positioning member being adjustable relatively to the supporting members for rendering the rack convertible to use in carrying shoes in upright position, and means for holding the positioning member in various positions of adjustment.

60 7. A shoe rack comprising a plurality of members, operative normally for supporting shoes in inverted position, a shoe-positioning member extending across the shoe-supporting members, and means for co-operating with the shoe-positioning member to locate it in either one of a plurality of positions along the shoe-supporting members.

65 8. A shoe rack comprising a frame, end members supported in the frame, a pin bar connecting the end members, shoe-supporting members mounted on the pin bar, a movable bar extending across the pins, and grooves in the end members for co-operating with the movable bar to locate it in either one of a plurality of positions along the pins.

70 9. A shoe rack shelf for carrying shoes either bottom side up or right side up, comprising end members, a plurality of shoe-supporting members and a movable bar extending across the shoe-supporting members, the end members being provided with grooves for receiving the bar to hold it in position to act as a heel stop for shoes carried right side up, the end members also being provided with grooves for receiving the bar to hold it in position to act as a toe rest for 75 shoes carried bottom side up.

75 10. A shoe rack shelf comprising end pieces, a connecting member and a back rail, shoe-supporting members carried by the connecting member and back rail, the end pieces being provided with a plurality of sets of substantially vertically extending grooves, and a removable bar constructed and arranged to be positioned in one or another of the sets of grooves.

80 In testimony whereof I have signed my name to this specification.

WARREN E. COOMBES.
